L. A. KEMPTON

ROTARY SNAP SWITCH

Filed Dec. 16, 1923

UNITED STATES PATENT OFFICE.

LESLIE A. KEMPTON, OF BRIDGEPORT, CONNECTICUT, ASSIGNOR TO GENERAL ELECTRIC COMPANY, A CORPORATION OF NEW YORK.

ROTARY SNAP SWITCH.

Application filed December 16, 1926. Serial No. 155,260.

The present invention relates to electric switches, and more especially to rotary snap switches adapted to be actuated in either direction of rotation.

5 The object of my invention is the provision of an improved rotary snap switch which shall be of strong and sturdy construction, well adapted to withstand the severe hammer blow stresses incident to the 10 normal operation thereof and which may be economically manufactured.

One embodiment of the invention is shown in the accompanying drawing, in which Fig. 1 is an axial section of a complete switch; 15 Fig. 2 is a plan view of the base and metal parts mounted thereon; Figs. 3 and 4 are axial sections of the actuating handle with the parts showing in normal and displaced relation; Fig. 5 is a plan view of the movable switch member; Fig. 6 is an exploded perspective view of the parts of the handle; Fig. 7 is a similar view of the parts for 20 mounting the ratchet pawl upon the movable switch member; Fig. 8 is a perspective view 25 of the parts of Fig. 7 in assembled relation; and Fig. 9 is a top plan view of the same.

The switch as shown in the drawing is 30 designed to control electric heater circuits, and is known in the art as a three heat reversible switch. The base 1 is of moulded insulating material having embedded therein a stop plate 2 of sheet steel with four spaced stop projections 3 formed by displacing upward sections of metal, each at 35 the juncture of two slots disposed at right angles, while symmetrically disposed with relation to the stop projections 3 in a metal hub 4 which extends through the base and provides a fixed bearing in which is journaled the switch shaft 5 having near one 40 end pairs of notches formed in opposite sides for the reception of a slotted washer 6 and a slotted cam 7 which bear against opposite ends of the hub 4 and hold the shaft against 45 axial displacement. Stationary contacts 8, 9, 10 and 11 are mounted at distributed points on the base and secured thereto by set screws 12 in the usual manner.

50 The movable member of the switch comprises a set of switch blades 13 and 14 of phosphor bronze or other sheet metal with

their centers cut out and mounted upon polygonal blocks of insulation 15 with intervening barrier disks 16. The blocks 15 and disks 16 are mounted upon a polygonal metal hub 17, which is bored out axially and journaled upon the shaft 5, whereby the shaft is permitted to turn freely therein during the tensioning of the snap spring and while the movable switch member is held 60 from turning by the pawl or detent 18 in engagement with some one of the stop projections 3.

55 The detent 18 is provided at one end with oppositely disposed shoulders 19 for engagement with the sides of the stop projections 3, while the opposite end is apertured to fit the slotted cam 7 whereby, upon partial rotation of the shaft 5, the detent is caused to retract and advance. A bent up lug 20 is provided 65 on the detent between the shoulders 19 which enters a radial slot 21 in a crank plate 22 attached by riveting to the lower end of the hub 17. In order positively to anchor the 70 crank plate to the hub 17 so that it may not 75 work loose under the hammer blows incident to the sudden stopping of the momentum of the movable switch member first in one direction and then in the other, I provide an anchor plate 23 of heavy sheet metal having 80 a central aperture 24 of a shape and size to fit very tightly about the end of the polygonal hub 17 while at opposite points in the outer edge are two notches 25 for the reception of corresponding bent up lugs 26 on the 85 crank plate 22.

85 After these parts of the movable switch member have been assembled upon the hub 17, a metal washer 27 is placed on top and riveted to the hub. The washer 27 has a 90 bent up spring engaging crank arm 28. A second washer 29 is fixed to the shaft 5 just above the washer 27 and has a spring engaging crank arm 30 adapted to rotate inside the arm 28. The method of fixing the 95 washer 29 upon the shaft is indicated in Figs. 1 and 5 and consists in providing the shaft 5 with opposite side notches 31 and the washer with a keyhole slot 32 so that upon passing the shaft through the larger 100 end of the keyhole until the side notches 31 are brought into the plane of the washer and

then by a sidewise shift of the latter it is secured against relative rotation therein and to prevent it from backing off sidewise I provide an integral lug 33 adjacent the large 5 end of the keyhole which is bent down therein after assembly of the washer on the shaft.

The snap spring 34 is shaped into two concentric helices with the free ends 35 thereof extended radially outward into engagement with the bent up arms 28 and 30. In 10 order to hold the spring in proper position radially and axially of the shaft, I provide a spider 36 consisting of a washer with a plurality of arms 37 struck up therein and spaced to enter the inner helix of the spring while its center is apertured to fit the shaft 5. It is detachably held in place by a slotted washer 38.

The switch mechanism is enclosed by an 20 insulatively lined metal shell 39 and through its top the free end of the shaft 5 projects for the reception of the actuating handle 40, which for proper functioning must be adapted to turn the switch in either direction and 25 also yieldingly to hold the enclosing shell 39 pressed against the base. A chafe plate 41 of suitable anti-friction material is interposed between top of the shell 39 and the adjacent end of the handle 40.

30 The handle 40 is of insulating material and made cup shape to enable it to be readily grasped externally by the hand and to receive in its interior cavity 42 the several parts necessary to permit it to be locked to 35 the shaft, yieldingly engage the shell 39, and readily detached without the use of tools. The cavity 42 is provided at opposite sides with two extensions to serve as guide ways 43 for the reception of lugs 44 on the 40 retaining nut 45 by which the handle is secured to the shaft. The nut 45 is yieldingly pressed inwardly of the cavity 42 by a cone shaped helical spring 46 which surrounds the shaft and thrusts against a keyhole locking disk 47 secured against a shoulder 48 in the cavity by a spring hoop 49 snapped into an annular groove adjacent said shoulder 48. The keyhole of the disk 47 is shaped to permit it to slide freely over the end of 50 the shaft 5 and the lug or feather 50 struck up therein, and the disk is provided at opposite edges with lugs 51 adapted to enter the guide ways 43, whereby it is positively prevented from turning relative to the handle 40.

55 The parts of the handle and shaft connecting means are shown in their normal positions in Fig. 1 with the keyhole disk 47 engaged by the lug or feather 50 on the shaft. In order to remove the handle, it is only necessary to pull upon it axially of the shaft against the tension of the spring 46 sufficiently for the keyhole disk 47 to clear the outer end of the feather 50, whereupon 60 it may be turned backhandedly and the nut

45 unscrewed from the shaft in well known manner.

While I have shown and described the best embodiment of the invention known to me, I do not desire to be restricted thereto.

70 What I claim as new and desire to secure by Letters Patent of the United States is:

1. In a snap switch, the combination with a base having a stop plate mounted thereon, of a movable pole piece provided with a hub, 75 a shaft extending through said hub and journalled in said base, a cam carried by said shaft, a detent movable into and out of engagement with said stop plate by said cam, a crank plate mounted on said hub 80 and operatively connected to said detent, and an anchor plate securely fixed upon said hub and having shouldered engagement with said crank plate.

85 2. In a snap switch, the combination with a base having a struck up stop plate mounted thereon, of a movable pole piece having a polygonal metal hub, a shaft extending axially through said hub and journalled in said base, a spring operatively connecting said movable pole piece and said shaft, a cam fixed to said shaft, a detent movable into and out of engagement with said stop plate by said cam, a crank plate slidably engaging 90 said detent, and means for positively securing said crank plate to said movable pole piece comprising an anchor plate locked at its periphery to said crank plate and cut out at the center for a driving fit with said polygonal metal hub.

95 3. In a snap switch, the combination with a base having a stop plate mounted thereon, of a movable pole piece having a square metal hub, a shaft extending loosely through said hub and journalled in said base, a spring operatively connecting said movable pole piece and said shaft, a detent movable by said shaft into and out of engagement with said stop plate, a crank plate slidably connected to said detent and provided with 100 bent up peripheral lugs, and means for securing said crank plate in fixed relation to said square hub comprising an anchor plate having a central aperture adapted to make a driving fit with said hub and in its periphery two opposite notches for the reception 105 of the bent up lugs.

110 4. In a snap switch the combination with the actuating shaft and movable pole piece thereof, of crank arms fixed respectively to said shaft and pole piece, a spring for engaging said crank arms comprising two concentric helices, and a spider plate mounted on said shaft over said spring and adapted to retain it in position both radially and axially of the shaft.

115 5. In a snap switch, the combination with the actuating shaft and movable pole piece thereof, a crank arm disk secured to said movable pole piece, said shaft having side 120

125

notches formed therein adjacent said crank arm disk, a second crank arm disk provided with a central keyhole aperture and a bent up lug adjacent thereto whereby the shaft ⁵ is adapted to be entered in the larger end of the keyhole aperture and its slotted portion to be entered sidewise into the narrower end of said aperture and secured therein by depression of said lug into said larger end of said aperture, and a coiled spring adapted to engage said crank arms.

In witness whereof, I have hereunto set my hand this 14th day of December, 1926.

LESLIE A. KEMPTON.
